UNITED STATES PATENT OFFICE

RANDOLPH MONRO, OF EDGEWOOD, MARYLAND

DRINKING MASK

Application filed June 25, 1929. Serial No. 373,640.

(GRANTED UNDER THE ACT OF MARCH 3, 1883, AS AMENDED APRIL 30, 1928; 370 O. G. 757)

This invention described herein may be manufactured and used by or for the Government for government purposes, without the payment to me of any royalty thereon.

5 This invention relates in general to respiratory apparatus and more particularly has reference to a gas mask allowing access of free flowing agents, other than air, out of contact with the surrounding medium.

10 Previous to this time, the gas masks employed in warfare and industry have not allowed for taking nourishment or stimulants while wearing the mask. In numerous instances, such as in gas attacks of long duration and mine accidents, it has been necessary to remove the masks heretofore employed if it was desired to partake of food, or drink, thus giving rise to unnecessary casualties.

15 It is obvious also that any attachments on a mask for connection with specially constructed containers will not allow for sustaining persons in emergencies of the character described where such accessories are not usually available. Even if access to a mask is afforded however, ordinary containers cannot be utilized with any safety, as the contents are likewise exposed to contamination.

20 An object of this invention is to provide a gas mask allowing access of free flowing agents, other than air, out of contact of the surrounding medium.

25 Another object of this invention is to provide a gas mask through which free flowing agents may be consumed or administered.

30 A further object of this invention is to provide a gas mask allowing access of free flowing agents out of contact with the surrounding medium, having an attachment communicating with the mask for automatically opening and sealing ordinary tins containing such agents.

35 A still further object of this invention is to provide a gas mask allowing access of free flowing agents out of contact with the surrounding medium, having an attachment for procuring such agents from an ordinary container, and replacing with purified air, the portion of agents consumed in the container.

A still further object of this invention is to provide a gas mask allowing access of free flowing agents, out of contact with the surrounding medium, having an attachment for opening ordinary tins containing such agents 55 and maintaining a seal from the surrounding medium in the event of detachment with the mask or removal from the tin.

With these and other objects in view which may be incident to my improvements, the invention consists in the parts and combinations to be hereinafter set forth and claimed, with the understanding that the several necessary elements comprising my invention, may be varied in construction, proportions 60 and arrangement, without departing from the spirit and scope of the appended claims.

In order to make my invention more clearly understood, I have shown in the accompanying drawings means for carrying the 70 same into practical effect, without limiting the improvements in their useful applications to the particular constructions, which for the purpose of explanation, have been made the subject of illustration. 75

In the drawings forming part of this specification:

Fig. 1 is a top view of the preferred form of angle tube.

Fig. 2 is a sectional view of the tube shown 80 in Fig. 1.

Fig. 3 is a bottom view of the tube shown in Fig. 1.

Fig. 4 is a modified form of the angle tube shown in Fig. 1. 85

Fig. 5 is a sectional view of the angle tube shown in Fig. 4.

Fig. 6 is a side view of the separate valve unit.

Fig. 7 is a sectional view of the valve unit 90 shown in Fig. 6.

Fig. 8 is a top view of the adapter.

Fig. 9 is a sectional view of the adapter taken on line 9—9 of Fig. 8, showing the mechanism inserted in an ordinary container. 95

Fig. 10 is a side view of the adapter.

Fig. 11 is a horizontal sectional view taken on line 11—11 of Fig. 9.

Fig. 12 is a horizontal sectional view taken on line 12—12 of Fig. 9. 100

Referring more particularly by numerals to the drawings in which the same and similar elements are designated by like symbols of reference throughout, and more especially to Figs. 1 and 2, there is shown the novel respiratory valve comprising an annular plate having the usual downwardly projecting rim for receiving the edges of a conventional facepiece. A plurality of deflector tubes integrally formed in V-shape, are provided on the top of the plate 1 for passing the inhaled air over the eye pieces of the mask to prevent clouding the vision.

The deflector tubes 2 and 3 communicate with a stem 4 on the under side of the plate for connection with a hose which may be attached to a suitable canister or other device for purifying air contaminated with any objectionable gases or smokes, or to supply oxygen to the wearer. The opposite end of the plate is provided with an upwardly projecting stem 5 for receiving a conventional flutter valve to afford an exit for the exhaled air. The angle tube in the preferred form is die cast or otherwise integrally made, preferably of some suitable light metal or alloy, so that a composite structure is presented.

This invention contemplates casting on bloc with the bottom of the angle tube, a downwardly extending cylindrical projection 6 in which is formed a pair of tubes 7 and 8. The tube 7 is preferably concentric with the projection 6 and communicates with an inverted L-shaped mouthpiece 9, integrally cast on the plate 1 between the deflector tubes and opening adjacent the mouth of a person wearing the mask.

The tube 8 opens into the top of the plate 1, thus affording communication with the interior of the mask. A plurality of conventional tire valves, of the type used in the valve stems of inner tubes, 11 and 12, are mounted in the tubes 7 and 8 for a purpose to be more fully hereinafter described, and the bottom of the projection 6 provided with an annular indentation 13, for receiving the rim of a sleeve on an adapter shown in Fig. 9.

The adapter comprises a cylindrical body portion 14, having the lower end formed with a tapered extension 16. The top of the extension 16 is provided with a circumferential depression 17 for receiving a rubber stopper 18, held at the top by an integral annular shoulder 19. A plunger 20 having a central bore 21 is mounted in the cylindrical body portion 14 of the adapter, designed to slide in a tubular sheath 22. The lower portion of the plunger 20 is formed with a reduced extension 23 terminating in point 24 having formed therein a series of orifices 25, communicating with the bore 21.

The end of the tubular sheath is tapered as at 26 and provided on the inside with a rim 27 adapted to act as a seat for spiral

spring 28, surrounding the reduced extension 23, and held at the other end against the body of the plunger 20. The tapered end of the sheath 22 is formed with a series of serrations 29. It will thus be seen that the plunger 20 may be pushed out of the sheath 22 against the force of the spring 28.

The outside of the plunger 20 is indented on one side, as shown at 31, and a portion of the sheath adjacent cut away as shown at 32. The side of the extension 16 is provided with an aperture 33 to allow communication with the interior of the tube 14. When the sheath 22 is forced upward against the action of the spring 28, however, the aperture 33 is closed by the wall of the sheath 22 and passage of air cut off.

A closure 34 provided with a series of apertures 35 is formed near the top of the sheath and provided with a centrally located upright pin 36. It is intended that a short section of hose 37 be employed for connecting the angle tube to the adapter and held thereon in any suitable manner such as by a tape 38.

When the hose 37 is pushed over the projection 6, on the angle tube, the rim of the sheath 22 on the adapter will fit in the annular indentation 13 on the bottom of the projection 6, and thus press down against the stem on the valve 12 and open the same, allowing air from the mesh to enter the adapter. The prong 36 concomitantly presses against the stem on the center valve 11 opening it in the same manner, allowing passage of free-flowing agents through mouthpiece 9.

When the adapter is attached, a person wearing the mask may thus obtain fluid from the tin in which it is inserted through the adapter and angle tube, and finally out of the mouthpiece 9. It is apparent that as the fluid is removed it will be replaced by air from the interior of the mask, from the passage 8 communicating with the mask and passing into the container through the adapter.

Another form of angle tube, for use in connection with a separate valve unit, is shown in Figs. 4 and 5. The deflector tubes 2 and 3 are formed on the plate 1 in the same manner as that shown in Fig. 1 together with the flutter valve stem 5. The lower portion of the L-shaped mouthpiece, however, is made up as a part of the hose connection stem 4, by a partition 41 provided on the interior, thus affording a tube 42 protruding from the mouth of the stem, adjacent the inner side of the wall.

The valve unit comprises a section of tubing 43 having the projection 6 integrally formed on one side. A partition 44 is formed against the side of the tube adjacent the projection 6 and communicating with the bore 7 to provide a tube 45, extending above

the tubing 43, and allow communication of the bore 6 with the tube portion 43.

It is intended that the stem 4 and the end of the tube section 43, be joined by a suitable 5 hose 46 and the tubes 42 and 45 connected by a rubber tubing 47. The bottom rim of the tubing 43 is joined to a canister, or other air purifying device, through a hose 48 in the same manner as the hose stem 4 shown 10 on the angle piece in Fig. 2.

The operation of this invention may readily be understood by having reference to the adapter shown in Fig. 7 for connection with the projection shown in either Fig. 2 or 15 Fig. 7.

The adapter is clasped on the upper end and forcibly thrust through the top of a conventional container 49, preferably with a single blow. The spreading walls of the 20 point 24 and the tapered end of the sheath 22 will enlarge the rupture until the soft rubber stopper 18 is properly seated therein and the contents hermetically sealed from the surrounding medium.

25 The hose section 37 is then fitted over the projection 6 and a seal of the open end of the adapter from the surrounding medium insured. The seating of the rim of the sheath 22 in the annular indentation 13, on the projection 6, and the pin 36, which results in the opening of the valves 11 and 12, makes it possible to consume liquids held in the container through the mouthpiece 9.

30 The plunger 20 is maintained in position 35 against the pressure of the spring 28 by the binding effect of the ruptured edges of the container on the rubber stopper so that the sheath 22, when pressed against a container bottom, insures the automatic closing 40 of the valves 11 and 12, should the container be inadvertently dislodged before removing the adapter from the projection 6. It is manifest that when the adapter is removed 45 from the projection 6 that the valves are automatically closed by release of the pressure exerted by the rim of the sheath 22 and the pin 26.

It will be at once apparent that this invention is in nowise limited to the consumption 50 of the liquid foods but with some slight modification in the form of the adapter may be successfully utilized for administering anæsthetics in the field or other locations in which the air is contaminated with objectionable gases or smokes, as well as being used for allowing smoking while wearing the mask under similar conditions. It is to be understood also that the valves shown 55 or a secondary set in the adapter may be 60 manually operated in a manner to insure closing should pressure be released sufficiently to permit the stopper to become loosened from the food container regardless of the pressure on the sheath or whether it touches 65 the bottom of the container.

There is accompanied by this invention a gas mask allowing access of free flowing agents, other than air, out of contact with the surrounding medium, in which liquid may be secured from an ordinary tin container uncontaminated and the contents replaced with purified air, the device being hermetically sealed from the outer atmosphere, with provision for maintaining the seal should either the container or device 70 become disconnected from the mask.

75 While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the 80 scope of the appended claims.

85 I claim:

1. A mask comprising means to carry on respiration, means associated with the mask to procure free flowing agents from ordinary 90 containers, and other means to replace the agents removed with air exhausted from the mask.

2. A gas mask comprising a tube to admit to the interior of the mask material other than air used for carrying on respiration, a valve mounted in the tube to regulate the flow of material and a plurality of valves for the exit of air in the mask, one for breathing exhausted air into the material 100 admitted to the mask.

3. A gas mask comprising a tube to admit to the interior of the mask material other than air used for carrying on respiration, a valve mounted in the tube to regulate the 105 flow of material, and means to direct air from the mask used to carry on respiration to the source of the other material.

4. A gas mask comprising an integral extension having a plurality of conduits 110 formed therein, valves mounted in the conduits, an annular depression formed in the end of the projection, and means adapted to be seated in the depression to operate the valves to admit material other than air to 115 the interior of the mask and to direct the air exhausted from the mask into one of the said conduits.

5. A gas mask comprising means to deflect admitted air over the eye pieces of 120 the mask, means for the exit of spent air, a projection having a plurality of conduits formed integral with the valve structure, a tubular extension formed over one of the conduits for carrying material other than air to the mouth of the wearer, valves mounted in the conduits and an annular depression formed in the end of the projection for receiving means adapted to operate the 125 valves mounted in the conduits to admit 130

material other than air, and to direct the air exhausted from the mask into the admitted material.

6. A gas mask comprising a conduit for admitting air in the mask, a tube extension for admitting material other than air used for carrying on respiration to the mouth of the wearer incorporated in the conduit, a detached portion of the air admittance conduit having a similar tubular extension incorporated therein connected separately to the conduit and tubular extension, and means to admit material other than air used for carrying on respiration into the detached tubular extension communicating with the mouth of the wearer.

7. A gas mask comprising a conduit for admitting air in the mask, a tubular extension for admitting material other than that used for carrying on respiration to the mouth of the wearer incorporated in the conduit, a detached portion of the air admittance conduit having a similar tubular extension incorporated therein connected separately to the conduit and tubular extension, a projection formed on the detached conduit having conduits communicating with the interior thereof and all the tubular extension valves mounted in the conduits, an annular depression formed in the end of the projection, and means communicating with a source of material other than air used for carrying on respiration adapted to be seated in the depression for operating the valves.

8. A device for recovering fluid from a container out of contact with the surrounding medium comprising means to rupture a receptacle, means incorporated in the rupturing means operative by rupturing of a container to afford passage of the contents of the receptacle entry to a gas mask, and means associated with the rupturing means to retain the device in the receptacle and seal the receptacle.

9. A device for recovering fluid from a container out of contact with the surrounding medium comprising means to rupture a receptacle, means incorporated in the rupturing means operative by rupturing of a container to afford passage of the contents of the receptacle entry to a gas mask, means associated with the rupturing means to retain the device in the receptacle and seal the contents, and means operated by the last named means to allow entry of the contents of the receptacle to a gas mask.

10. A device for recovering fluid from a container out of contact with the surrounding medium comprising a hollow piercing member for rupturing a receptacle, and a sheath mounted over the piercing member having a resilient stopper mounted thereon adapted to retain the device in a receptacle and seal the contents, the rupturing device being adapted to allow the passage of ma-

terial therethrough when fitted in a receptacle.

11. A device for recovering fluid from a container out of contact with the surrounding medium comprising a hollow piercing member for rupturing a receptacle, a spring operated sheath mounted over the piercing member having a resilient stopper mounted thereon adapted to retain the device in a receptacle and seal the contents and means forming the top of the sheath to allow entry of the contents of the receptacle to a gas mask.

12. A gas mask comprising means to admit material from ordinary containers other than air used for carrying on respiration to the interior of the mask, and other means associated with the mask for replacing the material removed from the container with air exhausted from the mask and which has been used for carrying on respiration.

13. A gas mask comprising a face plate member having an integral projection with a conduit formed therein, a tubular extension connected to said conduit to admit material other than air used for carrying on respiration to the mouth of the wearer, a tubular member adapted to be detachably secured to said projection to admit material through said conduit, a valve in said conduit, and means to automatically open said valve when said tubular member is attached to said projection.

14. A device for permitting the withdrawal of fluid from a container without allowing entry into the container of the surrounding medium comprising a tubular member adapted to rupture a container and be partially immersed in the fluid therein, said tubular member having a passageway for withdrawing fluid from the container and a second passageway for admitting air to the container, and a gas mask plate adapted to be attached to said tubular member and having passageways communicating with the passageways of said tubular member.

15. A gas mask comprising a faceplate member, a tubular member adapted to rupture a container and be partially immersed in a fluid therein, passageways in said members, means to detachably connect said members with their passageways in communication, valves controlling flow through said passageways, and means to open said valves when said members are connected and close them when said members are disconnected.

16. A gas mask comprising a member secured to the mask and having a passageway through which material other than air used for carrying on respiration may be admitted to the interior of the mask, a valve for controlling flow through said passageway, a tube detachably secured to said member and adapted to be inserted into a container, means

on said tube to open said valve by attachment of said tube and member and insertion of said tube into a container, and automatically operable means to close said valve upon detachment of the tube from the container.

5 In testimony whereof I affix my signature.
